UNITED STATES PATENT OFFICE.

GUY ALVERTICE COUNTRYMAN, OF ASHLAND, OHIO.

VEHICLE JACK.

Application filed July 3, 1924. Serial No. 724,007.

To all whom it may concern:

Be it known that I, GUY ALVERTICE COUNTRYMAN, a citizen of the United States, residing at Ashland, in the county of Ashland and State of Ohio, have invented certain new and useful Improvements in a Vehicle Jack, of which the following is a specification.

My invention relates to an improvement 10 in vehicle jacks of the double screw type, the improvement residing more particularly in the automatic stop mechanism hereinafter shown and described and claimed, whereby the screws are prevented from unscrewing 15 from each other and their common support while the jack is being operated. In general, my object is to provide a simple stop member adapted to travel upwardly with one of the screws into direct stop engagement with 20 a rotatable power-transmitting gear for the screws, and this stop member is also arranged and adapted to prevent the rotation of one of the screws while the other screw is being rotated by the gear.

25 In the accompanying drawing, Fig. 1 is a vertical section centrally through a vehicle jack embodying my invention, the screws being shown nearly at their limit of upward travel with the stop member about 30 to interrupt the rotation of the operating gear. Fig. 2 is a horizontal section of the jack on line 2—2 of Fig. 1 and Fig. 3 is a horizontal section on line 3—3 of Fig. 2. Fig. 4 is a perspective view of a modified 35 form of stop member. Fig. 5 is a vertical section of the jack on line 5—5 of Fig. 1, showing the stop member raised to stop the operating gear. Fig. 6 is a bottom view of the operating gear, and Fig. 7 a sectional view thereof.

The jack comprises a tubular body or standard 2 having vertical channels 3—3 at opposite sides thereof. These channels extend the full height of the standard and are 45 open full length to the central chamber of the standard, and also open to the top of the standard where a rotatable bevel gear 4 is adapted to be seated upon the standard within a recessed enlargement 5. A bevel pinion 6 having an operating shaft 7 journaled within an offset 8 of the standard may be used to rotate gear 4 which in turn is adapted to rotate a main lift screw 9 having screw-engagement with the internal screw-threads 50 at the upper end of the standard. Driving keys 11 fixed within gear 4 extend into

longitudinal side slots or key-ways 12 in screw 9, and the screw is free to move vertically while gear 4 is held in a fixed revoluble position upon the standard by a 60 cover plate 14 having a central opening 15 for the screw. The bottom face of gear 4 is recessed and formed with one or more radial stop shoulders 16 which travel in a circle across the open top ends of vertical 65 channels 3—3' when gear 4 is rotated, thereby permitting a stop member 17 to be projected into the recessed bottom of gear 4 where stop shoulder 16 may engage the same during the rotary movement of the gear, 70 providing the stop member has been raised to its limit in channel 3.

The means for supporting and controlling the movement of stop member 17 consists of a rod or bar 18 which is suspended 75 from the bottom of a second tubular elevating screw 19 having screw-connection with the upper end of hollow lift screw 9. The two screws and bar 18 are adapted to telescope together within hollow standard 2, 80 and bar 18 is square in cross-section to prevent the inner elevating screw 19 from revolving while the main lift screw is being rotated by gear 4, and bar 18 is prevented from turning by stop member 17 which is 85 in the form of a round rod with one end portion bent at right angles to provide a stop finger upwardly adapted to extend in channel 3, the opposite end of the rod being projected into the opposite channel 3'. Stop member 17 also acts as a guide for bar 18, and if desired both ends of this member may be bent at right angles as shown at 90 20—20 in the modified form of stop member 21 in Fig. 4. However, where only one end 95 is bent at right angles the stop member may be readily removed from its receiving opening 22 at the lower end of bar 18 to permit said bar and screw 19 to be given a half-revolution or more before replacing the stop member, whereby the two screws may be 100 adjusted lengthwise in respect to each other in assembling operations so that one screw will not project beyond the other or engage the bottom prior to the other when the screws are fully telescoped within the hollow standard. A second opening 23 may be used in bar 18 at right angles to opening 22 to permit quarter-turn adjustments, and such adjustments facilitate assembling because in machining the threads it is difficult to start the threads for each screw in 105 110

the same place radially at the end of the screw.

6 The bottom of hollow standard 2 is provided with a closure plate 24 and to prevent the screws from striking and dislodging this plate the standard is provided at its inner side with inwardly-extending ears or lugs 25 to arrest the descent of lift screw 9. When both screws are fully telescoped within each other and the standard 10 the tops of the screws are substantially flush with the top of cover plate 14, and the angular stop member 17 is resting at the bottom of standard 2. Rotation of gear 4 rotates 15 the main lift screw 9 which is forced upward because of its screw connection with standard 2. Rotation of screw 9 imparts an independent lift and extensible movement to the smaller elevating screw 19 which is 20 free to travel vertically but is held from rotation by bar 18 and member 17. A differential movement takes place between the 25 two screws, the upper or inner elevating screw 19 traveling faster than the lower or outer lift screw 9. As a result the inner elevating screw 9 will eventually pick up and lift bar 18 and carry the angular stop finger of member 17 into the bottom recess of revolving gear 4 where its upper end will 30 be engaged by one of the stop shoulders 16 thereby preventing further revolution of the gear and further upward movement of the screws. This stopping action is timed to occur before the main screw can unscrew 35 itself from standard 2, thereby preventing any possibility of the jack from collapsing accidentally or by careless manipulation of the jack during lifting operations.

What I claim, is:

40 1. A vehicle jack, comprising a standard, a lift screw in screw connection with said standard, a gear rotatably mounted upon said standard and splined to said screw, and telescopic means connected with said screw 45 having a stop member slidably engaged with said standard adapted to engage said gear at its bottom during the final upward movement of said lift screw.

50 2. A vehicle jack, comprising a standard, a main lift screw having screw connection with said standard, a second screw having screw connection with said main screw, an operating gear connected with said main screw and rotatably mounted upon said 55 standard, a device adapted to slidably engage said standard to prevent rotation of said second screw, said device being adapted to travel upwardly with said second screw and carrying a stop member adapted to engage the bottom of said operating gear.

60 3. A vehicle jack, comprising a channelled standard, a main lift screw having an operating gear mounted upon said standard, a

second screw carried by said main screw having a device suspended therefrom adapted to travel in said channeled standard and prevent rotation of said second screw, and said device comprising an angular stop member affixed to its lower end adapted to engage and stop said operating gear.

65 4. A vehicle jack, comprising a tubular standard having a vertical side channel, a main screw in screw-connection with said standard, a rotatable gear mounted upon said standard and connected with said main screw adapted to permit said screw to be elevated, a second screw in telescopic screw connection with said main screw, a bar suspended from said second screw having a cross piece adapted to travel in said side channel, said gear having a stop shoulder and said cross piece having an upwardly-extending part adapted to be elevated at one side of the lower portion of said main screw into stop relation with said shoulder.

70 5. A vehicle jack, comprising a main lift screw having an operating gear provided with a beveled stop shoulder at its bottom, and a second screw having a bar suspended therefrom provided with a vertically-extending stop member adapted to be raised into engaging position with said stop shoulder during the final stages of upward movement of said lift screw.

75 6. A vehicle jack, comprising a main lift screw having an operating gear, a second elevating screw operatively connected with said main screw, a bar suspended from said second screw, and a stop member detachably connected with said bar having a vertical projecting finger adapted to be raised into stop engagement with the bottom of said operating gear.

80 7. A vehicle jack, comprising a hollow standard, a pair of elevating screws and a bar adapted to be telescoped within said standard, vertical guides in said standard, a rotatable gear mounted upon said standard adapted to operate said screws having a stop shoulder at its bottom, and a cross member affixed to said bar adapted to engage said vertical guides, having a right-angled extremity extending upwardly at one side of said screws adapted to be engaged by said stop shoulder when said screws are elevated to approximately their maximum height.

85 8. A vehicle jack, comprising a hollow standard, a pair of elevating screws and an operating gear mounted upon said standard, said standard having a short inwardly-extending projection cast integral at its bottom adapted to provide a stop rest for said screws when lowered into said standard.

In testimony whereof I affix my signature.
GUY ALVERTICE COUNTRYMAN.
